UNITED STATES PATENT OFFICE.

PAUL L. COYLE, OF CORAOPOLIS, PENNSYLVANIA, ASSIGNOR TO WITHEROW STEEL COMPANY, OF PITTSBURGH, PENNSYLVANIA, A CORPORATION OF PENNSYLVANIA.

DIE ROLLING.

Application filed July 23, 1925. Serial No. 45,509.

The present invention relates to die rolling, and is directed toward the lengthening of the life of the roll from which die rolled articles are produced.

- 5 In the co-pending application of Wm. P. Witherow, No. 527,202, filed Jan 5, 1922, there is disclosed a method of die rolling by which longitudinal flash portions are rolled on the side of the article, these flash portions 10 accommodating the excess metal and being formed by such metal running out between the matrix portions of the two rolls.
- I have found that if a sharp corner between the matrix portion of the roll and the peripheral roll surface is left on the roll, the matrix deteriorates very much faster than it does if the corner is blunted or broken down to produce a fillet at the junction of the article proper and the flash 20 portion which is integral therewith. I therefore provide for blunting or breaking down this corner so that the flash portion is connected to the article by a small fillet. This fillet has no effect on the final product as 25 the flash is sheared from the article at the fillet. The life of the roll is materially lengthened by such provision and the accuracy of the rolled product may be maintained over a far greater period. This last 30 is true because the sharp corners formerly found on die rolls would roughen up and seemed to grip the hot metal in such manner as to prevent the matrix from filling out as it should do to produce an article of desired 35 dimensions and smooth surface.

In the accompanying drawings, which illustrate more or less diagrammatically one embodiment of my invention,—

Figure 1 is a section of a matrix portion 40 of a die roll constructed in accordance with my invention;

Figure 2 is a section through a die rolled article produced in the matrix of Figure 1;

Figure 3 is a view of a die rolled axle 45 blank produced in accordance with my invention showing the filleted flash attached to the axle blank; and

Figure 4 is a similar view showing the trimmed blank.

50 In the illustrated embodiment of my invention, there is shown a roll body 2 having a matrix portion 3 cut therein. The dotted line indicates the section which it is desired to produce, and it will be noted that the sharp corner of the rolled metal which

would obtain if the peripheral surface P of the roll were continued to meet the outline of the matrix portion 3, has been blunted or broken down by removing a small quantity of metal at the corner, as indicated at 4. 60 The quantity of metal removed from the corner need not be great, but it should be sufficient to give a reasonably blunt corner at the junction of the matrix surface and the peripheral roll surface so as to produce 65 a definite fillet on the article.

Figure 2 shows a section of an article produced in the matrix of the roll shown in Figure 1 and its mating roll. It will be seen that this section consists of a body portion 5 having integral flash portions 6 on opposite sides thereof. These flash portions 6 are connected to the body portion 5 by fillets 7 which result from the breaking down of the corners on the matrix as above 75 described.

Figure 3 is a plan view of a complete axle blank with the flash portions thereon. It will be seen that the fillets 7 extend substantially the entire length of the flash portions. This is highly desirable not only in that it materially lengthens the life of the roll, but also because experience shows that with the corners of the matrix portion thus blunted or broken down there is less roughening of the side wall in the roll matrices and better results are obtained in rolling on this account.

The provision of a blunted corner on the roll matrix brings about a decided improvement in the product. For example, in the rolling of rear axles somewhat like that shown in Figure 3, it was found where rolls having a sharp matrix corner were used that a decided gutter or undercut appeared in 95 the portion 5 of the article adjacent the junction of the axle proper and the flash 6. This undercut was so deep that even though the flash was very closely trimmed it still appeared in the article. By the provision of 100 the blunted corners as herein disclosed the difficulty was entirely overcome and articles up to desired dimensions were secured.

These fillets, which may be either angular, radial or of any desired configuration, do 105 not affect the final product as they are removed during the operation of shearing the flash portions from the article proper. On Figure 2 I have indicated by dotted line marked S the places where the flash portions 110

are sheared from the body, and it will be seen that the fillets are entirely removed so that the final axle blank is smooth and circular, as shown in Figure 4.

5. By the practice of my invention the life of the die rolls may be materially increased and a higher quality of product may be secured. The filleting is particularly important in those portions of the article 10 where a heavy reduction from the leader is effected, as naturally these portions of the roll are subject to the greatest wear.

While I have illustrated one form of my invention, it will be understood that it is 15 not so limited as it may be otherwise embodied or practiced within the scope of the following claims.

I claim:

1. The method of die rolling which includes forming a die rolled blank having integral flash portions, said flash portions forming no part of the finished article, there being a fillet at the junction of the article and the flash, and separating the 25 flash from the article at the fillet.

2. The method of die rolling which includes forming a die rolled blank having integral flash portions, said portions forming no part of the finished article, the flash 30 being joined to the article by a fillet, and separating both the flash and the fillet from the article.

3. The method of die rolling which includes forming a die rolled blank having integral flash portions, said portions forming no part of the finished article, the flash being joined to the article by a fillet in those 35 portions of the article where a heavy reduction is effected in the die rolling step, and removing the flash from the article at the fillet.

4. As a new article of manufacture, a pair of die rolls having matrix portions terminating in the roll peripheries, such matrix 45 portions being adapted to form a die rolled article when a leader is passed between them, the peripheral portions of the rolls adjacent said matrices being adapted to form a flash which is ultimately to be severed from the article formed in the 50 matrices, the corner formed at the junction of a matrix portion and the adjacent peripheral surface of the roll being blunted.

5. As a new article of manufacture, a pair of die rolls having matrix portions terminating in the roll peripheries, such matrix portions being adapted to form a die rolled article when a leader is passed between them, the peripheral portions of the rolls adjacent 55 said matrices being adapted to form a flash 60 which is ultimately to be severed from the article formed in the matrices, the corner formed at the junction of a matrix portion and the roll material at the corner of a matrix portion and the adjacent peripheral 65 surface being broken down so as to produce a fillet on the article joining the article proper and the flash.

6. As a new article of manufacture, a die 70 rolled blank having an integral flash adapted to be severed from the finished article, the flash being connected to the article proper by a fillet.

7. As a new article of manufacture, a die 75 rolled blank having a body portion and diametrically opposite flash portions adapted for ultimate removal from the body portion, said flash portions being strip-like and being connected to the article by fillets.

8. As a new article of manufacture, a die 80 rolled blank having a body portion and diametrically opposite flash portions adapted for ultimate removal from the body portion, said flash portions being strip-like and being connected to the article by fillets, the 85 fillets extending substantially the entire length of the flash portions.

9. As a new article of manufacture, a die 90 rolled blank having a body portion and diametrically opposite flash portions adapted for ultimate removal from the body portion, 95 said flash portions being strip-like and being connected to the article by fillets, the fillets extending along the flash over at least those portions of the article where a heavy reduction in the die rolling step has been effected.

10. As a new article of manufacture, a die 100 rolled blank having a body portion and an integral flash portion adapted for ultimate removal from the body portion, the line of separation between the flash portion and the body portion being substantially well defined but nevertheless provided with a fillet.

In testimony whereof I have hereunto set my hand.

PAUL L. COYLE.
